UNITED STATES PATENT OFFICE.

LOUIS LEFRANC, OF TRACY-LE-VAL, FRANCE.

PROCESS OF EXTRACTING SUGAR FROM JUICES, SIRUPS, &c.

SPECIFICATION forming part of Letters Patent No. 325,349, dated September 1, 1885.

Application filed June 12, 1885. (No specimens.)

To all whom it may concern:

Be it known that I, LOUIS LEFRANC, a citizen of the Republic of France, residing at Tracy-le-Val, in the said Republic, have invented a new and Improved Process of Extracting Sugar from Juices, Sirups, and Molasses, of which the following is a specification.

It is well known that when there is dissolved in a saccharine solution a quantity of lime sufficient to saturate the sugar which is contained in the solution a soluble sucrate of lime is formed. If this solution of sucrate of lime is subjected to the action of heat, there is obtained an almost insoluble solution of another sucrate, corresponding to the formula of tribasic sucrate, $(C_{12}H_{11}O_{11}3CaO)_2$. The formula of this reaction appears to be the following: $3(C_{12}H_{11}O_{11}2CaO) = 2(C_{12}H_{11}O_{11}3CaO) + C_{12}H_{11}O_{11}$. This sucrate is separable when heated by filtration from its mother-waters. The sugar can be disengaged from it by causing the lime to pass into an insoluble state or utilizing it for the purification of saccharine juices and sirups. The inconvenience of this process will appear from the preceding formula.

The transformation of sugar into tribasic sucrate is never complete. It is then necessary either to recommence and repeat many times the preceding operations upon the liquid as it becomes more and more spent, or else to resort to the process of substitution. Whatever may be the value of these two systems, it results clearly from the preceding formula that this process of extraction of sugar does not give good results, except when the quantity of sugar in the liquid is quite considerable—that is to say, from five to twelve per cent. of sugar.

It is also well known that there has been applied to the extraction of sugar from juices, sirups, and molasses the following process, which consists in dissolving in the saccharine solution a quantity of lime sufficient to produce a saturation of the sugar which the solution contains corresponding with the formation of the bibasic sucrate, afterward to add to this solution a certain quantity of the salt of lime in solution, corresponding with the quantity of lime which is lacking to obtain an insoluble sucrate, and to add to the mixture an

alkaline base. By this process there is obtained cold a precipitate of bibasic sucrate of lime by virtue of the reaction $3(C_{12}H_{11}O_{11}2CaO) + CaCl + NaO = 3(C_{12}H_{11}O_{11}3CaO) + NaCl$, in 55 the case, for example, of the employment of chloride of lime and of soda. This process, which the above theoretic formula indicates as perfect in the sense that all the sugar will be completely transformed into insoluble sucrate, has never received any serious industrial application, because of the expense of the soda, and, above all, because the presence in too great quantity of this reagent renders the filtration impossible. This process only finds 65 its application in cases where the saccharine liquors operated upon contain a very small quantity of sugar.

It results, from what precedes, that the first system only gives good results when the 70 liquors contain a very considerable quantity of sugar, while the second, on the contrary, is only useful when the liquid contains little sugar. Observing this, I have sought, by combining the two and somewhat modifying 75 them, to profit by the advantages which they present and to do away with their inconveniences. I have thus inaugurated a new process of treating molasses, which is the subject of the present invention.

The process is divided into two operations—the first comprising the formation of an insoluble sucrate, the second comprising the treatment of the mother-waters of this sucrate to extract the sugar therefrom.

First operation—formation of an insoluble sucrate.—The molasses or the drainings are brought in a stirring apparatus to a sugar strength of five to ten per cent. by means of a cold milk of lime containing lime to the extent of fifty to eighty per cent. of the weight of the sugar contained in the solution. This quantity of lime will be insufficient to produce a complete reaction; but it presents the advantage of commencing it without sudden 95 elevation of temperature—a condition essential to a large formation of bibasic sucrate, which only, as is known, is that which is most completely decomposed by heat into tribasic sucrate and sugar. When the mixture is quite 100 homogeneous and this reaction takes place, I make an addition of quicklime reduced to a

powder as impalpable as possible, and I continue to stir until the complete saturation of the sugar by the lime is completed. The addition of the quicklime represents fifty to seventy per cent. of the weight of the sugar. It should be made a little at a time to prevent elevating the temperature of the mixture, which would otherwise be produced. The saturation of the sugar being obtained, I filter, 10 by means of bags or filter-presses, the sucro-calcic solution, to separate the excess of lime which it contains, and I convey it to a boiler to be submitted to the action of heat. In proportion as the temperature rises up to the temperature of 50° centigrade the liquid becomes thick by reason of the formation of tribasic sucrate, which takes place completely when it arrives at the point of ebullition after the formula 15 $3(C_{12}H_{11}O_{11}2CaO) = 2(C_{12}H_{11}O_{11}CaO) + 2C_{12}H_{11}O_{11}$. This point being attained, the excess of lime which I had eliminated to facilitate the transformation of soluble sucrate into insoluble sucrate is added little by little to the liquid, which is always maintained at the point 20 of ebullition. The return to the work of this excess of lime presents two important advantages: it prevents the loss of sugar and renders the sucrate in a better condition for washing, giving it by the presence of an excess of lime more porosity, and consequently more permeability.

It is known that the tribasic sucrate of lime is a gelatinous body, and consequently difficult of filtration. The presence of an excess 35 of lime causes the disappearance of this grave defect. Thus in my system the lime is taken away when its presence is hurtful, and, on the contrary, replaced in the liquid when its presence has become necessary.

40 When the mixture is effected, I separate the insoluble sucrate from its mother-waters by sending it, at the temperature above indicated, to the washing filter-press, either by means of pumps or by means of a monte-jus. The sucrate remains in the apparatus in the form of cakes, which I wash with boiling water, the mother-waters flowing away to be submitted to the second operation. The sucrate thus formed is collected and placed in a stirring 45 apparatus, where I make of it a milk of a dilution which renders it suitable either for the liming of juices or sirups.

Second operation—the treatment of the mother-waters.—The mother-waters collected in the preceding operation containing yet about 55 three per cent. of sugar, the preceding process cannot further be applied with success without restoring these mother-waters to their primitive sugar strength by the addition of a new quantity of molasses. Now I have found, in doing this, inconveniences which have led me to reject it. I prefer to employ the following process: The mother-waters pass from the filter-press into any suitable refrigerator, 60 to be brought to a normal temperature, or are sent, if circumstances permit, directly into a tank, where they are allowed to cool. When

they are cooled, I add to them a quantity of quicklime in excess, to largely saturate with lime the sugar which they contain, in a manner to form, as previously described, a soluble sucrate. The addition of quicklime may even be made before cooling, provided that before the operation which succeeds the most favorable temperature to the formation 75 of this soluble sucrate has been attained. As in the first phase of the work, these mother-waters have extracted from them by filtration, for the same reason, their excess of lime. Then they are sent into a boiler, which may 80 be furnished with a stirring apparatus.

It is to be remarked here that in view of the small proportion of sugar the addition of quicklime, even in excess, does not sufficiently raise the temperature to form monobasic sucrate. I shall have then almost exclusively bibasic sucrate; but as by the action of heat this bibasic sucrate is converted into tribasic sucrate and into sugar, which would be lost or would necessitate an ulterior operation, I add, in the boiler, a solution of chloride of lime in sufficient quantity to form an insoluble sucrate of lime; I mix intimately; I heat; then I add a quantity of caustic soda in proportion equivalent to that of the chloride 95 of lime to be decomposed. As soon as this addition is made, cold or hot, the reaction takes place. Under the action of heat the bibasic sucrate of lime is decomposed, as is known, into tribasic sucrate and into sugar; but on the other hand the lime set at liberty by the substitution of the sodium of the soda for the lime of the chloride of lime is found in a nascent state, which facilitates its combination with the sugar already set at liberty, and, 100 finally, all the sugar is obtained in a state of tribasic sucrate.

As I have said, the operation may be made cold; but it is preferable to use heat, which facilitates the preceding combination, and, 105 moreover, facilitates the ulterior filtration.

When a temperature for the separation of the sucrate is attained, I send the liquid to the filter-press, in which it is formed into cakes, which are washed and collected, to be 115 employed as hereinabove stated in describing the first operation.

The excess of lime which had been previously eliminated may be added to that of the first operation, or replaced, if desired, in the 120 mother-waters, after precipitation of the sucrate.

The mother-waters may afterward be treated to extract from them the saline azotized and organic matters, or be directly utilized for fertilizers.

It will easily be understood that in the second operation, which I have just described, I may substitute for the chloride of lime any salt of lime whatever; also, that I may replace 130 the soda by any alkaline or alkaline earthy base whatever without departing from the principles on which my invention is based.

Even though the two operations described

may suffice to completely exhaust the saccharine liquors, I reserve to myself the right to repeat them, if necessary.

What I claim as my invention, and desire 5 to secure by Letters Patent, is—

1. The improvement in the art of extracting sugar from saccharine liquid, consisting in adding to the liquid more than sufficient milk of lime and quicklime in powder to produce 10 a soluble sucrate of lime, filtering the solution to remove the excess of lime, heating the filtered solution to about 100° centigrade, returning to the solution the lime previously removed by filtration, refiltering to separate 15 the tribasic sucrate of lime from the mother-waters, then adding quicklime to the resulting mother-waters, filtering the mixture to extract the excess of lime, adding to the filtered liquid, first, a salt of lime in sufficient quantity 20 to form tribasic sucrate of lime, and afterward an alkaline or alkaline earthy base to transform the remaining sugar into tribasic

sucrate of lime, and, finally, filtering the liquor from the sucrate, all substantially as herein described.

2. In the process of converting the sugar of saccharine solutions into sucrate of lime by first adding lime to produce a bibasic sucrate solution and afterward heating that solution to obtain the tribasic sucrate, the filtering of 30 the excess of lime from the bibasic solution before heating, and the re-addition of the so extracted lime after the cooling and before the subsequent filtration of the tribasic solution, substantially as and for the purpose herein 35 set forth.

In testimony whereof I have signed this specification in the presence of two subscriving witnesses.

LOUIS LEFRANC.
